Jacob Felbel

UNITED STATES PATENT OFFICE.

JACOB FELBEL, OF NEW YORK, N. Y., ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,115,292.

Specification of Letters Patent. Patented Oct. 27, 1914.

Application filed July 6, 1912. Serial No. 707,963.

To all whom it may concern:

Be it known that I, JACOB FELBEL, citizen of the United States, and resident of New York city, in the county of New York and State of New York, have invented certain new and useful Improvements in Type-Writing Machines, of which the following is a specification.

My invention relates to typewriting machines and has for its principal object to improve the type bars and hangers thereof.

To the above and other ends my invention consists in certain features of construction and combinations and arrangements of parts, all of which will be fully set forth herein and particularly pointed out in the claims.

My invention is illustrated in the accompanying drawings in which—

Figure 1 is a side elevation of a type bar and hanger and some of the associated parts of a typewriting machine, the segmental support for the type bars being shown in section. Fig. 2 is a fragmentary front elevation of a section of the type bar segment with a hanger secured thereto and having my invention embodied therein. Fig. 3 is a section of the hanger on the line $x-x$ of Fig. 1 and looking in the direction of the arrow at said line. Fig. 4 is an isometric view of a stiffener or tie-plate and sleeve. Fig. 5 is a side elevation showing a modification of my invention. Fig. 6 is an isometric view of a tie-plate embodying a second modification.

All of the figures of the drawing are on an enlarged scale.

In the drawings, my invention is shown applied to a type bar hanger of the Monarch typewriter. This is a front-strike machine having a platen indicated at 1 and having type bars 2 adapted to strike against the front face of said platen. Said type bars are supported on a vertical segment 3 by means of long hangers 4 and shorter hangers 5 secured to the front face of the segment 3 by screws 6 which take into threaded holes 7 in the segment. It will be noted in Fig. 1 that said segment is made with two steps, the shorter hangers 5 being secured to the face of the inner step, and the longer hangers 4 being secured to the face of the outer

or forward step, all as is well-known in the art. The short hangers 5 consist of simple loops of sheet metal having bearings 8 therein, each hanger thus being bifurcated or U-shaped and supporting a type bar pivoted thereto in the manner well-known in the art. The longer hangers 4 are also forked and are made of strips of sheet metal bent up into the form best shown in Fig. 3 and comprising arms connected together at one end by the bend 4^a in said strip of metal, and between the free ends of which the transverse type bar pivot 10 is supported in the bearing openings 11. The two arms or branches of this hanger are secured together by a cross-connecting device which is here shown as consisting of a rivet 12, and between said rivet and the screw 6 said arms or branches are formed with inwardly directed curves 13 to give access to the screws 6 of the shorter hangers 5. The particular one of said shorter hangers shown in Fig. 1, has its screw 6 threaded into the hole marked 7^a in Fig. 2, and it will be seen that this screw would be inaccessible on account of the long hanger 5 if it were not for this curve 13 in said long hanger.

It has been found in practice that type bar hangers in general, and the long hangers in particular, are subject to a certain amount of flexure especially under the violent jerks with which type bars are operated. This gives rise to more or less vibration of the type bar, resulting in more or less imperfect alinement. The amount of this vibration is, of course, greater in comparatively long hangers than it is in comparatively short ones, and it is also greater, other things being equal, where the branches are curved or formed with a neck as at 13. The U-shaped hangers of other typewriting machines also have bends in them, not of the precise forms of the bends 13 but of such character as to make the said hangers somewhat less stiff than they would be if they were straight. It is one of the objects of my invention to stiffen the hanger against the lateral vibration referred to. In most of these sheet metal hangers the bearings 8 and 11 are adjusted to the pivots 10 by upsetting the rivets 12 to a greater or less extent. Said rivets are headed up by repeated blows,

drawing the hanger arms together until said hanger arms and the bearings 11 are nicely adjusted to the type bar pivots, giving just the right degree of closeness of fit to cause 5 the type bar to move with precision but not to be tight and hard to operate. This method of adjustment has heretofore involved rather a nice operation and the result of the riveting has not always been as 10 good as could be desired. The last blow of the hammer that brings the hanger arms to exactly the right distance apart, sometimes raises on the head of the rivet a single bump or high spot which is the only point in the 15 head of the rivet that quite bears against the counter-sunk hanger arm. This hanger arm thus having but a point bearing on the rivet, that particular point when the machine is put into use soon works or beds 20 itself into the hanger arm or else is itself flattened out by the hanger arm, allowing the hanger arms to spring apart very slightly but still enough to result in a perceptible 25 looseness of the type bar pivot. By my invention the hanger is improved in respect to both of the matters above described.

I add to the hanger what may be termed a sleeve and tie-plate 14 illustrated separately in Fig. 4. This, in the form here 30 shown, consists of a strip, shank or stem of sheet metal which at one end is bent to form a sleeve 15 which surrounds the rivet 12 as shown in Figs. 1 and 3. From the sleeve portion 15 said plate has an inclined section or tongue 16, Fig. 1, extending downward and forward to the plane of the forward face of the hanger. Part of this section 16 lies between the forks of the hanger to resist lateral flexure thereof. The lower 35 end 17 of the plate lies flat across the forward edges of the hanger as shown in Fig. 1, the hanger being applied edgewise upon the segment, and the plate substantially parallel with the plane of said segment or support. 40 In order to avoid interference with the screws 6 of the shorter hangers 5, the plate 14 is formed with the cut-outs 18 substantially corresponding with the curved parts 13 of the hanger. The part 17 of said plate 45 is formed with a hole 20 preferably somewhat elongated, for the passage of the screw 6, by means of which the tie-plate is anchored at the securing end or root of the hanger. 50 The sleeve portion 15 is made of such length across the hanger that the rivet 12 can be headed up fully, drawing the hanger arms down firmly against the ends of the said sleeve. With this sleeve in place a 55 much more thorough job of riveting can be done without drawing the hanger arms too close together and after said riveting has been completed said hanger arms can, if necessary, be more nicely adjusted to the pivot 10 by a slight bending of the

hanger arms beyond the sleeve 15. It will thus be seen that this part of the tie-plate and the sleeve improves the rivet connections in the hanger arms, and also makes the operation of riveting a much simpler and 70 far less delicate one. When the hanger is secured to the segment as shown in Figs. 1 and 2 by means of the screw 6, the head of said screw also binds or clamps the tie-plate firmly upon the hanger and it will be seen 75 that the supplemental tie-plate or device makes said hanger far more rigid in a right- and left-hand direction. Forces acting in that direction on the hanger itself act on the metal of said hanger across its thin section whereas such forces act on the tie-plate edgewise in which direction said tie-plate is 80 very rigid. The tie-plate also stiffens the hanger in a direction parallel with that of the retaining screw 6, acting as a washer 85 between the hanger arms and the head of the screw and thus enabling the hanger to be more firmly secured to the segment.

In the Monarch typewriter each type bar is provided with a restoring spring 21 connected at one end to the type bar and at the other end to a fixed point associated with the type bar hanger. In the machine as at present manufactured these springs are connected to washers 22, which washers are 90 constructed as shown in Fig. 2 with an offset arm 23 and two holes 24, one for the spring of the type bar that is mounted in the long hanger and the other for the spring of that type bar which is mounted in the 95 short hanger 5, next and adjacent to the particular hanger 4 under consideration. In Fig. 2 it will be seen that the outer one of the two holes 24 is in line with the screw hole 7^a in the segment. I prefer to retain 100 this washer 22 for the sake of connecting the springs thereto. The tie-plate 14 is adapted itself to act as a washer as far as proper coöperation with the head of the screw 6 is concerned. This being true the 110 washer 22 may be omitted if desired and the tie-plate 14^a shown in Fig. 6 may be employed, said tie-plate being formed with an arm 25 bent back upon itself and having therein two holes 26 corresponding in position to the two holes 24 in Fig. 2.

A still further modification is shown in Fig. 5 where the hanger 4 is secured to the segment 3 by a screw 6 as before, the head of said screw coöperating with a washer 22 120 like that of Figs. 1 and 2. The tie-plate 14^b has the general characteristics of the tie-plate 14 but instead of coming toward the front of the machine and lying across the front of the bifurcated hanger it is introduced at the back of said hanger between the same and the segment 3. In some situations this form of tie-plate may be preferable to that of Fig. 1.

Various changes may be made without de- 130

parting from the spirit and scope of my invention.

What I claim as new and desire to secure by Letters Patent, is:—

1. In a typewriting machine, the combination of a hanger, a type bar pivoted to said hanger, means for supporting said hanger, and a tie-plate attached to the hanger at one place and at another place clamped between the hanger and its support.

2. In a typewriting machine, the combination of a hanger, a type bar pivotally mounted in said hanger, and a stiffening device attached to said hanger near the pivotal end thereof and anchored at the securing end thereof.

3. In a typewriting machine, the combination of a support, a hanger applied edgewise to said support, and a tie-plate or stiffener applied flatwise upon the hanger and secured thereto so as in effect to constitute a part of said hanger even when said hanger is removed from its support, and said tie-plate or stiffener being separately secured to said support.

4. In a typewriting machine, the combination of a support, a bifurcated hanger secured edgewise upon said support, a tie-plate secured thereto with its width at one point lying across the edges of said hanger and at another point lying between the arms of said hanger, and a type bar pivotally mounted on said hanger.

5. In a typewriting machine, the combination of a bifurcated hanger, a support to which said hanger is applied edgewise, a restraining plate arranged substantially parallel with the plane of said support and attached to the hanger at one place and anchored against the hanger at another place, and a type bar pivotally mounted in said hanger.

6. In a typewriting machine, the combination of a support, a hanger, means for fastening said hanger to said support, said hanger comprising two arms and a connecting rivet, a type bar pivotally mounted in said hanger, and a tie-plate attached to said rivet and clamped against the hanger by said fastener.

7. In a typewriting machine, the combination of a support, a forked hanger, means for securing said hanger to said support, a tongue or plate extending from the root of the hanger and arranged between the forks of the hanger to resist lateral flexure of the forks at a distance from said securing means, and a type bar pivotally mounted in said hanger.

8. In a typewriting machine, the combination of a forked hanger, a type bar pivotally mounted in said hanger, and a tongue or plate extending from the root of the hanger toward the pivotal end thereof

and there attached between the forks of the hanger.

9. A forked hanger having a cross connecting device or rivet, a collar or sleeve surrounding said cross connecting device and against the ends of which collar or sleeve the said forks are pressed, and a shank or stem connected with said collar and extending lengthwise of the hanger to the root or securing portion thereof. 70

10. A forked hanger having a cross rivet near its pivotal end, a collar or sleeve surrounding said rivet and against which the arms of said hanger are forced during the upsetting of said rivet, said collar or sleeve 80 having a tongue or extension which is clamped upon the root portion of the hanger by the securing screw of said hanger.

11. In a typewriting machine, the combination of a forked hanger having a cross connecting device, a collar or sleeve surrounding said cross connecting device and against the ends of which the said forks are pressed, and a stiffener for said forks connected with said collar. 90

12. In a typewriting machine, the combination of a hanger support, a forked hanger having a cross connecting device and a tie-plate extending between the forks of said hanger and against which said forks are forced by the tightening of said connecting device, said tie-plate extending back to said support and secured thereto. 95

13. In a typewriting machine, the combination of hanger arms joined at one end, a type bar pivoted in said hanger arms near the free ends of said arms, a tie-plate connected with both said hanger arms near said type bar pivot and extending lengthwise of 100 said hanger arms, said tie-plate lying crosswise of the edges of said hanger arms to stiffen said hanger arms in a transverse direction, a support, and means for securing said tie-plate and hanger arms to said support. 110

14. In a typewriting machine, the combination of a pair of sheet metal hanger arms connected at one end, a type bar having a transverse pivot journaled in said hanger arms near their other or free ends, a rivet 115 connecting said hanger arms between their ends, a tie-plate lying crosswise of said hanger arms and connected at one end to said rivet, a support, and means for securing said tie-plate and said hanger arms to 120 said support, said tie-plate serving to stiffen the hanger arms in a transverse direction.

15. In a typewriting machine, the combination of a pair of sheet metal hanger arms connected at one end, a type bar having a 125 transverse pivot journaled in said hanger arms near the free ends of said arms, a tie-plate extending lengthwise of said hanger arms and having its width crosswise thereof, the end of said tie-plate near said pivot 130

lying between said hanger arms, and means for drawing said hanger arms together against said tie-plate.

16. In a typewriting machine, the combination of a pair of sheet metal hanger arms connected together at one end, a type bar having a transverse pivot journaled in said hanger arms near their free ends, a tie-plate extending lengthwise of said hanger arms and having its width transverse of said hanger arms, the end of said tie-plate nearest said pivot lying between said hanger arms, and the other end of said tie-plate lying across the edges of said hanger arms, and a cross-connecting device for drawing said hanger arms together against said tie-plate.

17. In a typewriting machine, the combination of a pair of sheet metal hanger arms, a type bar having a transverse pivot journaled in said hanger arms near one end of said arms, a sheet metal tongue extending down between said hanger arms, and means for drawing said hanger arms together against said tongue.

18. In a typewriting machine, the combi-

nation of a pair of sheet metal hanger arms, a type bar having a transverse pivot journaled in said hanger arms near one end of said hanger arms, a sheet metal tongue extending between said hanger arms and bent at its end into a sleeve, and a rivet passing through said sleeve and connecting said hanger arms.

19. In a typewriting machine, the combination of a pair of sheet metal hanger arms connected together at one end, a type bar having a transverse pivot journaled in said hanger arms near their free ends, a rivet connecting said hanger arms between their ends, and a tie-plate extending lengthwise of said hanger arms and having its width transverse to said hanger arms and having its end near said pivot bent into a sleeve surrounding said rivet.

Signed at New York city, in the county of New York, and State of New York, this 5th day of July, A. D. 1912.

JACOB FELBEL.
